ORNAMENTAL RELIGIOUS SIGN

Stephen C. Cafiero, 8 Craig Place, Bloomfield, N.J.

Filed July 19, 1960, Ser. No. 61,536

Term of patent 14 years

(Cl. D1—12)

The FIGURE is a front elevational view of an ornamental religious sign embodying my new design, the rear being essentially plain and the sign being of no substantial thickness.

The dominant features of the design reside in the portions shown in full lines on the drawing.

I claim:

The ornamental design for an ornamental religious sign, substantially as shown and described.
